UNITED STATES PATENT OFFICE.

CHARLES T. WITTSTEIN, OF CHICAGO, ILLINOIS.

DESIGN FOR A SOLITAIRE-GEM SETTING.

SPECIFICATION forming part of Design No. 34,609, dated June 4, 1901.

Application filed April 25, 1901. Serial No. 57,503. Term of patent 14 years.

To all whom it may concern:

Be it known that I, CHARLES T. WITTSTEIN, a citizen of the United States, residing at Chicago, in the county of Cook and State of Illinois, have invented and produced a new and original Design for a Solitaire-Gem Setting, of which the following is a specification, reference being had to the accompanying drawing, forming a part thereof.

The drawing illustrates by a perspective view a solitaire-gem setting, showing my new design.

As shown in the drawing, the leading or material feature of my design consists of a bezel A and open-work B, presenting a support for the bezel. The bezel A has a grooved or concave inner peripheral face.

It is apparent that this design is applicable to solitaire-settings on finger-rings, shirt-studs, ear-rings, scarf-pins, and other like articles of adornment.

Having described my invention, what I claim as new, and desire to secure by Letters Patent, is—

The design for a solitaire-setting for gems, as herein shown and described.

In testimony whereof I have signed my name to this specification in the presence of two subscribing witnesses.

CHARLES T. WITTSTEIN.

Witnesses:

D. W. LEE,
ALBERT D. BACCI.
